UNITED STATES PATENT OFFICE.

CHARLES C. ABBOTT, OF PITTSFIELD, MASSACHUSETTS, ASSIGNEE TO GENERAL ELECTRIC COMPANY, A CORPORATION OF NEW YORK.

ELECTRIC HEATER.

Application filed April 8, 1925. Serial No. 21,872.

My invention relates to electric heaters and has for its object the provision of means for dissipating heat therefrom and for preventing overheating of a certain part or parts of the heater.

My invention relates more particularly to electric space heaters or air heaters such as may be used in heating rooms, street cars, etc. One form of this type of heater is described and claimed in my Patent No. 1,494,939, dated May 20, 1924, of which this invention is an improvement. In certain cases it is desirable to maintain the terminal ends of electric heaters at a comparatively low temperature, for example, where the terminal ends are sealed with a material having a comparatively low melting point.

In carrying out my invention I provide heating means for a central section of the heater, and heat dissipating vanes extending lengthwise of the heater provided with slots near their ends whereby conduction of heat to the ends of the heater is prevented.

For a more complete understanding of my invention reference should be had to the accompanying drawing in which Figure 1 is a side view partially in section of an electric heater embodying my invention; Fig. 2 is a sectional view along the line 2-2 of Fig. 1 looking in the direction of the arrows, while Figs. 3 and 4 are views similar to Figs. 1 and 2 showing a modified form of my invention.

Referring to Figs. 1 and 2 of the drawing, I have shown my invention in one form as comprising a helical coil, sheathed wire heating unit 10 of convenient length, such as described and claimed in my Patent No. 1,367,341, dated February 1, 1921. Briefly, this heating unit comprises an outer metallic sheath 11 in which a helical resistance conductor 12 is embedded in a compacted mass of powdered heat refractory insulating material 13. The insulating material 13 may be compacted to a hard dense mass having good heat conductivity by reducing the diameter of the sheath after the unit has been assembled. Such heating units can be bent easily into any desired shape and as shown the unit 10 is bent in form of a hairpin.

The resistance conductor 12 extends throughout a central or body section 11^a only of the sheath, and has its ends connected to terminal members 14 and 15 which are also embedded in the insulating material 13.

The terminal members extend throughout the end portions 11^b and 11^c of the sheath and project from the sheath for connection with a suitable source of electric supply. For convenience in securing the terminals to the resistance conductor, the ends of the terminals may be suitably threaded as indicated by reference characters 16 and 17 and the turns of the resistance conductor screwed on these threaded portions. This forms a good mechanical as well as electrical connection.

As shown, each end of the sheath is sealed to prevent the entrance of moisture. For example, each end of the sheath 11 may be threaded at 18 for a short distance, and a cup-like member or receptacle 19 having a threaded bore screwed on the threaded end 18. The member 19 is filled with a suitable sealing material 20, such as bakelite or an asphaltic compound. This sealing material is poured into the member 19, the unit being held upright with the member 19 uppermost, while heated to thinly liquefy it. The threaded end of the sheath extends into the interior of the cup a slight distance only. Suitably connected to the ends of the terminal members 14 and 15, as by brazing, are copper connectors 14^a and 15^a. These connectors extend into the cup members in close proximity to the ends of the sheath, a short gap being left between the inner end of each connector and the end of the sheath, which gap is filled with the sealing material 20. The inner ends of the connectors are beveled to allow the sealing material to flow readily into these gaps. It is essential that the sealing material fill the gaps thoroughly and make a good firm connection with the insulating material 13, which is exposed at the ends of the unit, so that there will be no air gaps and other weak points in the insulation formed by the sealing material between the terminal members and the ends of the sheath. The sealing material surrounds the connectors to the level of the cup members which have their inner edges beveled to provide greater creepage space between the connectors and the sheath. The connectors are provided with flattened portions 14^b and 15^b which are embedded in the sealing material and form anchors to prevent loosening of the connectors due to twisting when the electrical connections are made.

For the purpose of dissipating the heat

generated by the unit 10, the unit is clamped between two metallic plates 21 and 22 extending longitudinally thereof and forming together a heat dissipating member. The 5 plates are formed with registering hairpin-shaped grooves or recesses 23 and 24 respectively in which the heating unit 10 is placed and secured by welding the plates together as near the heating unit as possible in such 10 manner as to clamp the heating unit tightly and form a good thermal contact with the sheath 11. The welding of the plates may be carried out in any suitable manner, such as by a line welding or spot welding process.

15 The clamping plates 21 and 22 extend throughout the entire length of the hairpin-shaped unit 10, covering the central portion 11^a and the two end portions 11^b and 11^c. In order to interrupt the conduction of heat 20 from the central portion 11^a to the ends of the unit, slots are formed in the plates. As shown in Fig. 1 an internal slot 25 is formed in the plates substantially at the junction of the resistance conductor and the terminal 25 members. This slot 25 terminates at each end a short distance from the edge of the plates and serves to interrupt the continuity of the plates in a region adjacent the heating unit. Two additional internal slots 26 and 27, similar to slot 25, are provided at suitable intervals between the slot 25 and the ends of the heating unit. Between slots 25 and 26 are two aligned external slots 28 and 29 which are cut in toward each 30 other from opposite edges of the plates. These slots extend toward each other far enough to break away the metal of the plates around the heating unit. Slots 30 and 31, similar to slots 28 and 29, are provided between slots 26 and 27.

35 By means of the slots 25 to 31 inclusive, it will be observed that the metal of the plates is broken away adjacent the heating unit in such manner as to interrupt the conduction of heat through the plates, but without materially impairing the heat dissipating characteristics of the plates. It will also be observed that any heat which is conducted toward the end of the heating unit must follow a zigzag course through the plates. This construction plays an important part in maintaining the ends of the heating unit at a comparatively low temperature at which the sealing material 20 is not melted or appreciably softened.

40 The ends of the heating unit are also cooled by conduction through the connectors 14^a and 15^a. It is for this reason that the inner ends of the connectors are brought down as near as possible to the ends of the sheath. Furthermore by terminating the ends of the sheath near the bottoms of the cup members, the connectors are brought down near the bottoms of the cup members 45 so that lower temperatures are maintained at

these points, and therefore any tendency for the sealing material to be melted at the bottoms of the cup members is overcome.

50 In order to provide for more effective dissipation of heat by the plates 21 and 22, the plates are cut or slit from the slot 25 in a direction parallel with the two branches of the heating unit to a point near the bend of the heating unit. As indicated in Fig. 2, this cut in the plate 21 is near the lower 55 branch of the heating unit, while the cut in the plate 22 is near the upper branch of the heating unit. The two overlapping vanes 32 and 33 thus formed are bent apart to provide for the circulation of air between 60 them. Additional heat radiated surface is provided by the vanes 32 and 33.

65 It will be observed that heat is dissipated by the portions of the plates 23 and 24 adjacent the central portion 11^a of the heating unit substantially independently of the dissipation of heat by the portions of the plates adjacent the end portions 11^b and 11^c of the heating unit. A small amount of heat will be conducted through the sheath 70 11, the terminal members 14 and 15 and other parts toward the ends of the heater, but this heat will be rapidly dissipated.

75 In the modified form of my invention shown in Figs. 3 and 4 the heating unit 35, which is similar in construction to the heating unit 10, is shown as a straight length clamped between two metallic strips 36 and 37. Since the ends of the heater are identical in construction, only one end will be 80 described in detail. Slots 38 and 39 are cut in the plates from opposite edges toward the heating unit at the junction between the resistance conductor and the terminal member 40. Similar slots 41 and 42 are provided midway between the slots 38 and 39 and the end of the heating unit. Midway between these two sets of slots is a central slot 43, and between the slots 41 and 42 and the end of the heater is a similar slot 44.

85 The ends of the heater are provided with cup-like members 45 which are filled with a sealing material 46 substantially as described in connection with Fig. 1. In this form, however, a different form of connector, shown as a binding post 47, is secured, as by brazing, to the end of the terminal member 40 in place of the connector of Fig. 1. This binding post serves to conduct heat away from the end of the heating unit in 90 the manner previously described in connection with Fig. 1. The binding post receives heat by conduction from the end of the heating unit, which heat is dissipated into the surrounding air, and has an appreciable effect in cooling the end of the heating unit.

95 While I have described my invention as embodied in concrete form and as operating in a specific manner in accordance with the

provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States is—

1. An electric heater comprising a metallic sheath, a resistance conductor extending through a section of said sheath, a terminal for said resistance conductor extending through an end section of said sheath, and heat dissipating means extending lengthwise of said sheath in heat conducting relation therewith, the continuity of said heat dissipating means being interrupted substantially at the junction of said resistance conductor and said terminal, whereby heat is dissipated from said sections independently of each other.

2. An electric heater comprising a metallic sheath, a resistance conductor extending through a section of said sheath, a terminal for said resistance conductor extending through an end section of said sheath, and a heat dissipating member extending lengthwise of said sheath provided with a slot at the junction of said resistance conductor and said terminal for interrupting the conduction of heat through said member to the said end section.

3. An electric heater comprising a metallic sheath, a resistance conductor in a body section of said sheath, a terminal for said resistance conductor extending through an end section of said sheath, powdered heat refractory insulating material surrounding said resistance conductor and terminal, and a heat dissipating member extending lengthwise in heat conducting relation with said sheath, said member being provided with a slot adjacent the junction of said sections whereby heat is dissipated from said body section substantially independently of said end section.

4. An electric heater comprising a metallic sheath, a resistance conductor located in

a central section of said sheath, terminals for said resistance conductor extending through the end sections of said sheath, powdered heat refractory insulating material compacted around said resistance conductor and terminals, and a pair of metallic plates forming heat dissipating means between which said sheath is clamped, said plates being provided with slots at the junctions of said central section with said end sections whereby heat is dissipated from said end sections independently of said central section.

5. An electric heater comprising a U-shaped heating unit, a pair of metallic plates forming heat dissipating means between which said unit is clamped, said plates being slit and shaped to allow circulation of air between the branches of said U-shaped unit and provided with a series of internal and external slots for interrupting the conduction of heat to the ends of said unit.

6. An electric heater comprising a metallic sheath, a resistance conductor secured in said sheath in electrically insulating relation therewith, a receptacle secured to the end of said sheath, a sealing material in said receptacle, and a relatively heavy heat conducting member electrically connected to said resistance conductor extending into said sealing material in close proximity to said sheath.

7. An electric heater comprising a metallic sheath, a resistance conductor secured in said sheath, a terminal member for said resistance conductor projecting from said sheath, powdered heat refractory material in said sheath surrounding said resistance conductor and terminal, a relatively heavy heat dissipating connector secured to said terminal near the end of said sheath, a receptacle secured to the end of said sheath, and a sealing material in said receptacle surrounding said terminal member and connector.

In witness whereof, I have hereunto set my hand this 3rd day of April, 1925.

CHARLES C. ABBOTT.
